Primary Examiner — Cynthia Ramirez*Assistant Examiner* — Carrie A Matteoli(74) *Attorney, Agent, or Firm* — Accelerate IP LLC(57) **CLAIM**

We claim the ornamental design for a mat traction system, as shown and described.

DESCRIPTION

FIG. 1 is a top view of a mat traction system showing the new design;

FIG. 2 is a bottom view of a mat traction system showing the new design;

FIG. 3 is an enlarged top view of a mat traction system showing the new design;

FIG. 4 is a side view of a mat traction system showing the new design;

FIG. 5 is an enlarged side view of a mat traction system showing the new design;

FIG. 6 is a front isometric view of the mat traction system showing the new design; and,

FIG. 7 is an isometric enlarged view of the mat traction system showing the new design.

The broken lines in the drawings depict portions of the mat traction system that form no part of the claimed design. Additional dot-dash broken lines depict the boundaries of the enlarged areas and form no part of the claimed design.
